COMBINED LAMP SOCKET AND SWITCH

Frank D. Bryant, Stratford, and William R. Young, Fairfield, Conn., assignors to General Electric Company, a corporation of New York

Application April 9, 1941, Serial No. 387,634

1 Claim. (Cl. 173—350)

Our invention relates to a combined lamp socket and switch for tubular electric discharge lamps, for example, fluorescent lamps of the type now in commercial use.

An object of our invention is the provision of a lamp socket for tubular lamps which incorporates a switch for operating the lamp thereby obviating the necessity of a separate remote starting switch.

Another object of our invention is to provide an integrally arranged switch mechanism for a lamp socket of the type in which a tubular lamp is mounted by rotation, for example, a socket of the type shown and described in the Marshaus Patent Re. 21,545, dated August 27, 1940 and assigned to the same assignee as the instant invention.

In the accompanying drawing, Fig. 1 is a view of a tubular electric lamp mounted in sockets one of which is provided with an operating switch in accordance with our invention; Fig. 2 is a rear view of the socket showing the switch operating means; Fig. 3 is a view of the interior of the socket; Fig. 4 is an exploded view of the socket and switch elements; Fig. 5 is a sectional view through the socket taken along the line 5—5 of Fig. 3; and Fig. 6 is a front view of the socket showing the lamp prongs in seated position.

Referring to the drawing, we have illustrated a tubular electric lamp 10, for example, a fluorescent lamp, supported at each end in a lamp socket 11, the left-hand socket being provided with an operating switch in accordance with our invention. Each end of the lamp is provided with spaced contact prongs which support the lamp in the socket; the socket is shown by way of example as being of the type described in the Marshaus Patent Re. 21,545, assigned to the same assignee as the instant invention. The lamp prongs, designated 12, are shown in seated position in the socket by Fig. 6.

For a brief description of the socket of the Marshaus patent, reference may be made to Fig. 6. This socket comprises a housing 15 of insulating material, such as a molded plastic, in the front face of which is formed an annular opening 16. A slot 17 extends from the opening to the outer edge 18 of the housing. Disposed centrally of the opening 16 is a guiding stud 19 formed with a diametrical slot 20 in alignment with the slot 17. Contact members 21 and 22 are disposed within the housing on opposite sides of the stud 19 in the space defined by the opening 16. The lamp prongs are mounted in the socket by moving them laterally in align-

ment through the slots 17 and 20 until the lowermost prong contacts the edge of the opening 16; thereafter the prongs are rotated to bring them into engagement with the contact blades of the socket.

Turning now to our invention comprising a combined switch mechanism and socket and referring to Figs. 3 to 5, inclusive, it will be seen that we have provided the contact members of the Marshaus socket with a switch mechanism, the arrangement being such that current to the contact prongs of the lamp is controlled by the mechanism. In constructing the socket, the housing 15 is provided with a recess 23, in the side opposite that in which the opening 16 is formed, which recess is divided into two compartments 24 and 25 by a dividing wall 26. The wall is formed integrally with the housing and extends across the space defined by the opening 16 and carries the stud 19 which cooperates with the contact members and opening in the manner described above. The contact member 21 is located in the compartment 24; it is provided at its upper end with a lamp prong engaging recessed portion 27 and at its lower end with a laterally extending terminal portion 28 carrying a binding screw 29. The terminal portion of the contact member rests on ledges 30 in an enlargement 24' of the compartment 24 in the base 30 of the housing while the main portion of the contact blade is biased by an abutment 31 into engagement with the guide part 19. Accordingly, when the lamp prongs are seated in the socket, one of the prongs flexes the contact blade against the abutment 31, thereby insuring good electrical contact between the lamp prong and the corresponding socket contact.

The other contact 22 is likewise formed with a recessed portion 32 for receiving the other lamp prong, but instead of being provided with a terminal portion the blade 22 extends straight downwardly and rests on a ledge 33 in the enlargement 25' of the compartment 25 formed in the base of the housing. Located along the length of the contact member 22 is a switch blade 34 which is formed of flexible material such as spring bronze and which is fastened at one end in any suitable manner, as by spot welding, to the contact member 22 at the point 35. At its other end, the switch blade 34 is formed with a laterally extending arm 36 provided with a cam surface 37.

Cooperating with the switch blade 34 is an operating means comprising a carrier 38 of insulating material provided with an operating han-

dle 39 and a current conducting shorting member 40. The carrier 38 is rotatably mounted on the socket by means of a pin 41 extending into a bearing opening 42 formed in the wall 26. Co-operating with the shorting member is a second fixed contact blade 43 which rests upon the dividing wall 26; a portion of this blade extends beneath the rotatable carrier 38 and remains in contact with the shorting member 40. The opposite end of the blade 43 rests on a ledge 44 formed in the lower portion of the wall 26 and is provided with a laterally extending portion secured in any suitable manner, as by spot welding, to an angularly shaped terminal member 45. The terminal member is provided with a binding screw 46 for connection to the lamp operating circuit. In assembled position, the edge of the terminal member rests on a ledge 33' in the side wall of the compartment 25'. In order to insulate the fixed contact blade 43 from the movable contact member 22, a piece of insulating material 47, such as sheet fiber, is disposed between these elements. The insulating piece 47 is formed with two angularly extending arms 48 and 49, the part 48 resting between the lower end of the contact member 22 and the vertical arm of the terminal member 45 while the part 49 underlies the lower end of the fixed contact blade 43 and prevents accidental engagement with the contact member 22.

The recess 25 is covered by a closure means in two pieces. The lower portion of the recess is covered by a plate of insulating material 50, such as sheet fiber or the like, held in position by a screw 51 threaded into an opening 52 in the dividing wall of the housing. The closure plate bears tightly against the fixed contact blade 43 and holds it in position as well as the terminal member 45 and the insulating separator 47. For wiring the binding posts 29 and 46 the closure plate is formed with conductor receiving slots 53. The upper portion of the recess is closed by a cover member 54 which is formed of insulating material, such as a molded plastic. The member 54 is formed with a recess 55 for receiving the carrier 38 and with an opening 56 through which the handle 39 extends to the rear of the socket. The cover is held in position by a set screw 57 threaded into an opening 58 in the dividing wall 26. Since the fixed contact blade 43 rests on the wall 26, in order to avoid contact with the set screw, the blade is formed with an enlarged portion having an opening 59 through which the set screw passes without making contact therewith. This means that the exposed set screw 57 cannot make contact with the live parts within the housing. The cover 54 also serves to maintain the rotatable carrier 38 in position since the inner surface of the cover bears against the carrier and maintains the pin arbor 41 in the bearing recess 42. In this manner the shorting member 40 is pressed firmly into engagement with the upper end of the fixed contact blade 43.

The switch mechanism is operated simply by 65 rotating the handle 39 to turn the carrier 38. The carrier is shaped as a rectangle and the shorting member 40 extends around opposite edges of the rectangle so that it presents opposite exposed contact surfaces for engagement with 70 the cam surface 37 of the blade 34 which is

5 spring biased into engagement with the carrier at all times. Rotating the carrier presents either the shorting member 40 or the insulating edge of the carrier for engagement with the cam surface 37. Since the shorting member is at all times in contact with the fixed blade 43, a circuit is 10 closed between the terminal 45 and the socket contact blade 22 when the shorting member 40 and cam 37 make contact. Rotating the carrier another 90 degrees brings the insulating portion in engagement with the cam 37 opening the circuit through the switch.

15 Since the socket contact member 22 is flexed away from the guiding stud 19 and likewise away from the carrier upon insertion of the lamp prongs within the socket, the additional contact blade 34 is made of sufficient length and given sufficient bias to maintain the cam 37 in engagement with the carrier 38 at all times irrespective of the position of the contact member 22. The switch mechanism is extremely compact so that only a small increase in the size of the lamp socket has been necessary.

20 The combined lamp socket and switch is connected in circuit with the fluorescent lamp in the usual way so that the lamp cathode at the corresponding end of the lamp is in series with the terminal portions of the socket by mounting the lamp prongs in the socket. The socket at 25 the other end of the lamp is a conventional type. The cathodes at each end of the lamp are connected in series with the conventional starting mechanism and ballast by appropriate wiring to the sockets and the power supply. The switch mechanism then controls the supply of current to the lamp.

30 While our invention has been illustrated and described as incorporated in a lamp socket of the type described in the Marshaus patent, it should be manifest that it may be utilized with other forms of sockets since the operation of the switch is not dependent upon any particular form or arrangement of the lamp contacts. An 35 advantage of using a lamp socket of the type described is that it has been possible to provide an extremely compact arrangement of switch mechanism and socket.

40 What we claim as new and desire to secure by Letters Patent of the United States is:

45 In a supporting device for a lamp having spaced contact prongs, a housing of insulating material having two compartments separated by a wall, a contact member in each compartment for engaging the lamp prongs, one of said contact members being provided with terminal means for connection to a lamp operating circuit, the other contact member being normally insulated from the circuit, a switch blade carried by the said other contact member, a second switch blade mounted on said dividing wall and being provided with terminal means for connection to the lamp operating circuit, a member of insulating material rotatably mounted on said wall, a conducting element carried by said member, said conducting element being continuously in contact with said second-mentioned switch blade and adapted to engage said first-mentioned switch blade for placing the said other contact member in the lamp operating circuit.

50 FRANK D. BRYANT.
